US00D588636S

(12) **United States Design Patent**
Pyle

(10) **Patent No.:** **US D588,636 S**
(45) **Date of Patent:** ** *Mar. 17, 2009

(54) **SEQUENTIALLY THREE STEPPED
EXTENSION PLATE PAPER FILE**

(76) Inventor: **Lance R. Pyle**, 8264 Twin Oaks Ave.,
Citrus Heights, CA (US) 95610

(*) Notice: This patent is subject to a terminal disclaimer.

(**) Term: **14 Years**

(21) Appl. No.: **29/289,414**

(22) Filed: **Jul. 18, 2007**

(51) **LOC (9) Cl.** **19-04**

(52) **U.S. Cl.** **D19/33**

(58) **Field of Classification Search** D19/26-33;
D3/294, 299, 303; 28/78, 85; 40/530, 536,
40/537; 206/472, 556; 281/29, 19.1, 31,
281/21.1, 22; 402/8, 18, 19, 68, 73, 79, 14;

D6/457

(57) **CLAIM**

The ornamental design for a sequentially three stepped extension plate paper file, as shown and described.

DESCRIPTION

FIG. 1 is a right perspective view of the present invention.

FIG. 2 is a left perspective view of the present invention.

FIG. 3 is a plan view of the present invention.

FIG. 4 is a side view of the present invention.

FIG. 5 is a bottom view of the present invention; and,

FIG. 6 is a top view of the present invention.

1 Claim, 3 Drawing Sheets
